ANESTHETIC OF THE PYRIDINE SERIES AND
METHOD FOR PRODUCING THE SAME

Raemer R. Renshaw, New York, and Paul F. Dreisbach, Yonkers, N. Y., assignors to Pyridium Corporation, Nepera Park, N. Y., a corporation of New York

No Drawing. Application February 28, 1938,
Serial No. 193,079

9 Claims. (CL 260—295)

Our invention relates to anesthetics of the pyridine series and the method of preparing them.

It has been stated that the production of anesthesia is a property of the derivatives of the benzoyl group (Einhorn Liebigs Annal, 1900, vol. 311; 1902, vol. 325; 1908, vol. 359). It is even stated that the benzoyl group could not be replaced by any other acid radicals (Filehne, Ber. klin. Woch. 1887, p. 107; Ehrlich and Einhorn, Ber. 1894, p. 1870), and that the benzoyl group acted as an "anesthesiophore" group. Numerous local anesthetics have been made since the discovery of Einhorn, that the esters of p-aminobenzoic acid and hydroxybenzoic acid, and their various derivatives act more or less as anesthetics.

We have now found, that anesthetics can be produced from the pyridine ring, that is, we have produced anesthetics by esterification of alkyl hydroxypyridine carboxylic acids. We have also found that the anesthetics so prepared are less toxic than some of the analogous compounds of the benzene series.

The object of this invention is to prepare an anesthetic by esterification of p-hydroxypyridine carboxylic acids.

Another object of this invention is to prepare anesthetics of the pyridine series which are more effective than the corresponding compounds of the benzene series. Other objects of this invention can be seen from the specifications.

The general formula of the simple esters of p-hydroxypyridine carboxylic acid may be represented thus:

in which R represents the residue of an alkyl group.

Of these simple hydroxypyridine carboxylic acid esters, only the methyl and ethyl esters of nicotinic acid are known.

The hydroxy group may be alkylated for our purpose by replacing the hydrogen atom with an alkyl group containing up to 6 carbon atoms. The carboxy group may be esterified with amino alcohols, alkyl-amino alcohols, dialkyl-amino alcohols with two equal or different alkyl residues of any number of carbon atoms, or with cycloaliphatic residues such as the cyclohexyl group or cyclohexanyl group. Furthermore, N-alkyl-piperidine residue may be also used for the esterification.

These compounds may be represented with the following general formula:

in which R' represents the residue of an unsubstituted alkyl group having not more than 6 carbon atoms, R² represents the residue of an unsubstituted alkyl group and X represents the residue of an amino compound, alkylamino compound, dialkylamino compound or cyclic alkylamino compound.

R' in the general formula is an unsubstituted saturated alkyl residue, such as ethyl- to hexyl-residues, these alkyl radicals being selected from a group of monovalent radicals derived from a saturated hydrocarbon. It may be a normal or an isomeric alkyl group and it contains not more than 6 carbon atoms. Those with 3 to 5 carbon atoms appear to be the most effective.

R² in the general formula represents a saturated normal or isomeric alkyl group. Two or three carbon atoms appear to be the most desirable, though higher alkyl groups may be used in some instances.

To obtain the best results it is apparent that the hydrogen atoms in the amino group X should be substituted with alkyl groups. These alkyl groups again might be different or alike, but it is obvious, that dialkyl amines with equal substituents are easier to obtain.

The compounds prepared according to these specifications are colorless, basic in character and form addition salts with mineral and organic acids. The bases of the compounds in general are insoluble in water and soluble in most organic solvents. The salts are more or less soluble in water.

We have prepared several of the salts of these new basic compounds. The hydrochlorides, sulfates, hexaoxates, benzoates, cinnamates and phenyl acetates, some of which form difficultly crystallizable substances as will be noted in this specification.

In general they have anesthetic properties and their toxicity is comparatively low. The raw material for preparing these compounds are the chloropyridine carboxylic acids, made according to the methods described in the literature through various steps. For instance, 6-chloro-3-carboxypyridine (6-chloro-nicotinic acid) is prepared according to the method of V. Pechman, Welsch, (Ber. 17 (1884) 2392), or other known

methods. The final compound is made by substituting the chlorine with an alkoxy group and by esterification of the carboxy group.

Example 1

5   2 grams 6-methoxy nicotinic acid (prepared according to H. Meyer, M. vol. 28 (1907) p. 59) are dissolved in warm methanol, and to this is added a solution of 5 grams sodium in 10 cc. absolute methanol. The sodium salt forms a white precipitate, which is collected and dried. Now 2.25 grams of B-chloroethyl-diethylamine hydrochloride are dissolved in a few cc. of water, placed into a separatory funnel and made alkaline with sodium hydroxide solution. The separated free amine is now taken up with ether and the solution dried with flake caustic soda. To this solution is added the sodium 6-methoxy nicotinate and heated on the steam bath under stirring. When the ether evaporates an oil remains, which is dissolved in ether and washed with water several times. Then the ether is distilled off, the residue dissolved in dilute hydrochloric acid, and evaporated to dryness. The oily residue is recrystallized from ether-butyl alcohol mixture. It crystallizes in rosettes of needles. M. P. 116-118° C. The chemical reaction of the process is the following:

The resulting diethylaminoethyl-6-methoxy nicotinate is soluble in ether, chloroform and alcohols, and insoluble in water. With inorganic and organic acids it forms addition salts which are more or less soluble in water.

Example 2

45   From 4.2 grams B-chloroethyl-diethylamine hydrochloride the base is prepared as above. To the ether solution 3 grams finely pulverized sodium-6(iso) propyloxy nicotinate are added and heated on the steam bath under a reflux condenser for 3 hours. After evaporating the ether an oily residue remains. This is taken up with ether and washed with water several times. After evaporating the ether, normal hydrochloric acid is added to the residue until all is dissolved and the solution evaporated to dryness. For purification it is recrystallized from dry acetone. The white crystalline powder melts at 118° C.

The formula of this hydrochloride of diethylaminoethyl-6-(iso) propyloxy-nicotinate is as follows:

which was confirmed by analysis. In a nitrogen determination (micro-Dumas) there was found N=9.11%. Theoretical N=8.85%.

70   This hydrochloride is soluble in alcohols and acetone. On addition of alkalies to the solution the base separates, which is insoluble in water, and soluble in ether, chloroform and alcohols.

Example 3

75   From 2.5 grams B-chloroethyl-diethylamine

hydrochloride the base is prepared as above. To the ether solution 2 grams finely pulverized sodium 6-(n) butoxy nicotinate are added and heated on the steam bath under a reflux condenser for one and a half hours. After evaporating the ether an oily residue remains. This residue is treated as in Example 2 and the obtained hydrochloride of diethylaminoethyl-6(n) butyloxy nicotinate

is recrystallized from ether-absolute ethanol mixture. It forms fine colorless needles. M. P. 108-111° C. It is soluble in ether, dioxane and very soluble in alcohols and in water. The base of this substance, and the benzoate, cinnamate, phenylacetate and hexoate form difficultly crystallizable oils.

From 4.5 grams γ chloropropyl dibutylamine hydrochloride the base is prepared as previously described. To the ether solution 3.1 grams finely pulverized sodium 6-(n) butoxy nicotinate are added and heated on the steam bath for one and a half hours. After evaporating the ether an oily residue remains. This residue is treated as in Example 3 to obtain the hydrochloride of dibutylaminopropyl-6(n) butyloxy nicotinate:

35   This substance is soluble in ether, alcohols and water. The base is insoluble in water. Both the hydrochloride and the free base form a slightly yellowish colored oil.

The compounds prepared according to the methods described in the examples possess anesthetic properties. When a small quantity is placed on the tongue, one will promptly observe a lasting anesthetic action. For testing purposes the hydrochloride and other salts of the compounds were prepared and 0.5-2% solutions were used. Rabbits' eyes were flooded with the solution for 1 minute. The anesthesia in some cases lasted unusually long. The toxicity tests prove that they are relatively non-toxic.

50   These new anesthetics can be used in aqueous solutions by dissolving their salts; the hydrochlorides and benzoates having preference over the other salts. The bases dissolved in oil of sweet almond or other suitable oils can be used for injections or can be incorporated into ointments.

We do not limit ourselves to the specifically mentioned times, temperatures, quantities, chemicals, or steps of procedure as these are given simply to clearly describe our invention as set forth in our specification and claims, and may be varied without going beyond the scope of our invention.

65   *What we claim is:*

1. As a medicinal compound having anaesthetic properties, the dialkylaminoalkanol ester of 6-alkoxypyridine-3-carboxylic acid of the following general formula:

75   in which R' is an alkyl group containing 1 to 6

carbon atoms, R^2 is the residue of an alkyl group and R^3 is the residue of an alkyl group, these alkyl groups being unsubstituted and selected from a group of monovalent radicals derived from a 5 saturated hydrocarbon.

2. As a medicinal compound having anaesthetic properties, the water soluble salt of a dialkylaminoalkanol ester of 6-alkoxypyridine-3-carboxylic acid of the following general formula:

10

15 in which R' is an alkyl group containing 1 to 6 carbon atoms, R^2 is the residue of an alkyl group, R^3 is the residue of an alkyl group, these alkyl groups being unsubstituted and selected from a group of monovalent radicals derived from a 20 saturated hydrocarbon and Ac is an acid radical forming a water soluble salt.

3. As a medicinal compound having anaesthetic properties, the dialkylaminoalkanol ester of 6-alkoxypyridine-3-carboxylic acid of the following general formula:

25

30 in which R' is the residue of an alkyl compound containing 1 to 6 carbon atoms, R^2 is the residue of an ethyl group and R^3 is the residue of an alkyl group, these alkyl groups being unsubstituted and selected from a group of monovalent radicals derived from a saturated hydrocarbon.

4. As a medicinal compound having anaesthetic properties, the dialkylaminoalkanol ester of 6-alkoxypyridine-3-carboxylic acid of the following general formula:

40

45 in which R' is the residue of an alkyl group containing 1 to 6 carbon atoms, R^2 is the residue of an ethyl group, R^3 is the residue of an alkyl

group, these alkyl groups being unsubstituted and selected from a group of monovalent radicals derived from a saturated hydrocarbon and Ac is an acid radical forming a water soluble salt.

5. As a medicinal compound having anaesthetic properties, the dialkylaminoalkanol ester of 6-alkoxypyridine-3-carboxylic acid of the following general formula:

5

10 in which R' is the residue of an alkyl group containing 1 to 6 carbon atoms, R^2 is the residue of a propyl group and R^3 is the residue of an alkyl group, these alkyl groups being unsubstituted and selected from a group of monovalent radicals derived from a saturated hydrocarbon.

20 6. As a medicinal compound having anaesthetic properties, the dialkylaminoalkanol ester of 6-alkoxypyridine-3-carboxylic acid of the following general formula:

20

25 in which R' is the residue of an alkyl group containing 1 to 6 carbon atoms, R^2 is the residue of a propyl group, R^3 is the residue of an alkyl group, these alkyl groups being unsubstituted and selected from a group of monovalent radicals derived from a saturated hydrocarbon and Ac is an acid radical forming a water soluble salt.

30 7. As a new medicinal compound having anaesthetic properties, the hydrochloride of diethylaminoethyl-6(iso) propyloxy nicotinate.

35 8. As a new medicinal compound having anaesthetic properties, the hydrochloride of diethylaminoethyl-6-(n) butyloxy nicotinate.

40 9. As a new medicinal compound having anaesthetic properties, the hydrochloride of diethylaminopropyl-6(n) butyloxy nicotinate.
